FISHING ROD HOLDER OR THE LIKE

Frederick S. Ring, 717 S. Roswell Road, Marietta, Ga.

Filed Feb. 23, 1965, Ser. No. 83,941

Term of patent 7 years

(Cl. D31—4)

I claim:

The ornamental design for a fishing rod holder or the like, substantially as shown.
